UNITED STATES PATENT OFFICE.

GEORGE W. KNOFF, OF POTTSTOWN, PENNSYLVANIA.

FIRE DOOR OR WINDOW.

1,112,071.

Specification of Letters Patent. Patented Sept. 29, 1914.

Application filed July 23, 1913. Serial No. 781,085.

That which is may concern:

Be it known that J. GEORGE W. KNOFF, a citizen of the United States, residing at 1812 High street, Pottstown, Montgomery county, Pennsylvania, have invented certain new and useful Improvements in Fire Doors or Windows, of which the following is a specification.

This invention relates to fire doors or the like, such as windows, and has for its object to provide a door or the like of practical and reliable construction, which collapses compactly into a nest of slats to open the door or window opening and which, when extended to close the same, presents inner and outer walls with an intervening air space, and is entirely self-flashing, so as to constitute an effective, double-walled barrier to flame, heat, and the elements.

25 A further object is to provide for the efficient flashing of the door or window opening at the sides.

With these and other objects in view, the invention comprises the novel construction 25 and combination of parts hereinafter set forth and shown in the drawings, and more particularly pointed out in the claims.

In the drawings: Figure 1 is an elevation of a doorway closed by my collapsible door, which is here shown as provided with a wicket door; Fig. 2 is a vertical transverse section through the same showing the door closed, the intermediate portion of the view being broken away for economy of space; Fig. 3 is a similar view showing the relation of the slats and linkage when the door is collapsed into a nest of slats, thus opening the doorway. For clearness of illustration the construction is shown bulkier than is necessary, and it will be understood that in practice the slats will nest even more compactly than is indicated; Fig. 4 is a fragmentary vertical sectional view taken centrally of Fig. 2, being drawn on an enlarged 45 scale with intermediate portions broken away; Fig. 5 is a fragmentary plan view at the top of the door, which is in open or collapsed position, omitting part of the top or baff slat 12 but showing the counter- 50 weight gearing in plan; Fig. 6 is a fragmentary vertical section taken near the ends of several slats in closed relation; Fig. 7 is a detail view of an adjustable supporting part; Fig. 8 is a vertical section through the wicket door, the intermediate portion of which is broken away; Fig. 9 is a view illus-

trating the relation of the slats when the door is partially raised or collapsed so as to afford ventilation without entirely opening the doorway; Fig. 10 is a view diagrammatically illustrating the invention applied to a window opening; Fig. 11 is a semi-diagrammatic view showing in vertical section the upper part of an alternative construction, the slats being in overlapping or 60 extended relation; Fig. 12 is a similar view showing the collapsed condition; and Fig. 13 is a sectional detail view.

The invention is applicable to a fire door or the like, but for convenience it is shown 70 and described mainly as a door. Fig. 10 illustrates it embodied as a window shutter.

The door or window opening is designated 10 or 10^a. The collapsible door or shutter is composed of a plurality of turning or tiltable slats 11, which, as shown, are preferably of similar construction, and narrow or half slats 12, 13 at the top and bottom. The lower slats may be severed as indicated in Fig. 1 to form a wicket-door 80 opening, which may be closed and opened by a wicket-door formed of short slats 11^b. These latter in effect constitute sections of the slats 11, 13, from which they may be regarded as severed. The slats, including the 85 short slats or wicket-door sections 11^b, are adapted to turn transversely of the door or window opening and to be collapsed upward in compactly nested relation, as shown in Fig. 3, to open the doorway, and when extended to close the same are in overlapping relation, as shown in Fig. 2, the formation of the slats being such that their overlapping portions are bent or spaced away from each other so as to coöperate to form a series 90 of chambers 14, which together constitute a space intervening between inner and outer walls 15, 16. The construction of the wicket-door will be more particularly described hereinafter.

100 Each slat is preferably made of a single piece of sheet metal or other suitable fire-proof material, which is bent or curved into the desired shape. The particular shape of the slats 11 may, of course, be varied, but as 105 illustrated it is such that the upper and lower portions of each slat are offset laterally from each other so as to form parts of the inner and outer walls of the door, while its intermediate portion crosses over from 110 one wall to the other. In the particular embodiment of the invention shown, the slats

11 are covered in ogee or S-shape. The slats 12 and 13 are substantially halves of the ogee slats, and complete, respectively, the outer and inner walls of the door at the top and bottom. The outer wall of the door, it will be observed, is formed of the lower portions of the slats, so as to shed water, while the inner wall is formed of their upper portions. The upper and lower edges 17 and 18 of the slats, taken alternately, contact with opposite sides of, and are spaced apart on, the slats between; and the portions 19 of the slats between these edges constitute the intermediate portions referred to, which 15 cross the intervening space between the walls 15, 16 and form division walls between the pockets 11. It will be observed that this construction involves a relation wherein as to any two alternate slats the distance between the upper edge of the lower slat and the upper edge of the intermediate slat is less than the distance between the lower edge of the upper slat and the said upper edge of the intermediate slat, and vice versa. 20 This is to say, the adjacent edges of any two alternate slats 11 in effect extend past each other on the intermediate slat. In the particular construction shown, the result is that the upper edge 17 of each slat is at a higher 25 level than the lower edge 18 of the slat next but one above. The pivot for the intermediate slat lying between the upper and lower edges of the adjacent slats. Thus, the inner and outer walls 15, 16 of the door are continuously spaced, and, while it may be of nodular form in cross-section as shown, a predetermined minimum distance is preserved between the walls, which at no point between the top and bottom of the door approach 30 sufficiently close to each other to eliminate or unduly constrict the intervening air space.

As is indicated in the cross sectional views, the upper and lower edges of the slats are rolled over reversely, that is to say, inwardly at both sides of the door, for reinforcement and to afford an efficient bearing against the surfaces of the slats.

Means are provided whereby the slats may be turned and collapsed, or extended, 50 simultaneously. The particular construction may be varied, and, in fact, two embodiments are illustrated, both of which are in the nature of a lazy-tong linkage. In the construction shown in Figs. 2 to 6 two- 55 armed levers 20 are pivoted at their middle to the intermediate portions of the several slats, the ends of each lever being likewise pivoted to the upper and lower portions respectively of the adjoining slats. There are 60 preferably two sets of these levers located at opposite ends of the slats adjacent to the sides of the door opening. In the particular construction shown, the center pivots 21 are formed by studs projecting from plates 21^a riveted or otherwise secured to opposite

sides of the slats at the ends, while the end pivots 22 are on lugs 23 suitably secured to the inner surfaces of the slats. In the construction illustrated the distance between the pivots 21 is at all times less than the length of a slat. At the top and bottom the linkage is completed by short or single armed levers 24, 25. The slat 12 constitutes, in effect, the lower half of a slat 11, the upper half of which is cut off to avoid a single wall section at the top of the door, and the lever 24 corresponds to the lower half of a lever 29. In like manner the slat 13 and the lever 25 correspond to the upper half of a slat 11 and a lever 29, respectively. The lever 24 is pivoted at its lower end to the upper portion of the top slat 11, and at its upper end to the top of the short slat 12, a lug and a pivot being provided for the purpose. In like manner, the lever 25 is pivoted at its upper end to the lower portion of the bottom slat 11 and at its lower end to the bottom of the narrow slat 13 by means of a lug and a pivot 29. The construction constitutes in effect a lazy-tong, the levers 20, 24 and 25 forming one set of levers while the slats themselves form the other set. The pivot 26 is fixed, that is to say, it has no movement of translation, and is preferably in the form of a shaft which extends across the door so as to be common to the upper ends of the linkage at both sides; and is secured at its ends to the sides of the door opening, so as to form a support from which the door is suspended. The bottom pivot 29 is also preferably a rod extending across the door and common to both linkages, but is movable vertically toward the pivot 26. When a wider door is employed this rod may be sectional as hereinafter described. The result of raising the door at the bottom or of applying lifting force to the linkage at any height is to swing all of the levers and slats simultaneously, so that the slats all move upward and in so doing turn and approach each other, finally occupying the substantially horizontal nested positions shown in Fig. 3.

The door may or may not be counterweighted; but counterweights 30 are illustrated, which travel in vertical boxes 31 at opposite sides and preferably in rear of the door opening. These counterweights are shown connected with the ends of a rod 27, which extends across the door and the ends of which take the place of two of the pivots 21, by flexible connections 32, which latter extend upward over pulleys 33 at the top and thence down into the boxes 31 where they are secured to the counter weights. As shown the connections of the cables to the weights may be eccentric, that is to say on one side of the central axis of the weights, see Fig. 5, and in order to guide the weights in their movements.

cal rods 34 may be provided, passing through openings in the weights. The weight of the door preferably somewhat overbalances the weights, so that when the 5 door is down the weight of the door itself causes a positive pressure of all the edges 17, 18 against the surfaces of the slats, thereby insuring tight joints.

The door is adapted to be closed or extended by any suitable means, and likewise any suitable means may be provided for opening or collapsing it. In the particular construction shown means are provided for turning the pulleys 33 and therefore 15 by opening or closing the door; and for this purpose gears 36 are fixed to the pulleys and engaged by pinions 37 on a shaft 38 extending across the top of the doorway.

At one end of this latter shaft is a sprocket 20 or wheel 39 over which passes an endless chain 40 which hangs within convenient reach, so that by pulling on one course or other of the chain the door is either collapsed or extended.

25 When the door is in collapsed condition the nested slats may be protected and concealed within an open-bottom casing 52 at the top of the doorway. It will be understood that the vertical depth of this casing 30 will be proportioned to receive all of the slats when the door is collapsed; but in actual practice this depth will not be great because of the very compact manner in which the structure may be made to collapse.

The door is held against lateral movement and is guided in its vertical movements by vertical members 41 at the sides of the door opening. These members are 40 preferably composed of spaced angle-irons forming channeled guides, which receive central projections on the lazy-tong linkage. In the particular construction shown in Figs. 4 and 5 these projections are 45 formed by extensions of the pivot pins 21.

As shown in Fig. 5, the ends of the slats are recessed at 43 to receive the vertical members 41 and so as to form projections 42, which engage the sides of said members 35 and thereby flash the door opening. In the construction shown in Figs. 1 to 6 the recesses 43 are centrally disposed, and there are flashing extensions 42 at both sides of each guide. The said recesses are formed 55 entirely in the portions of the slats behind the outer wall 16, so that the latter extends without opening across the front sides of the guides; and, as shown, they are preferably formed in the intermediate portions 60 of the slats internal to both walls. It is preferably within these recesses 43 that the levers 20 extend across the slats, and in order to avoid the necessity of lengthening the recesses the intermediate portions of the 65 levers are offset as indicated at 44, thus en-

abling the levers to be accommodated in the recesses of the length shown when the parts are collapsed into the position indicated in Fig. 3.

In order to enable the bottom slats to 70 hang as close as possible to the bottom of the door opening, adjustable supporting means are provided for the door, in the nature of plates 45 (see Figs. 4 and 7) provided each with a vertical series of intersecting openings 46 for the reception of the corresponding end of the rod 26. These plates are secured rigidly to the sides of the door opening, and the intersecting openings enable a comparatively fine adjustment 80 of the hanging rod to be effected without the use of movable parts.

Figs. 11 and 12 show a construction differing from the foregoing in certain particulars. The collapsible supporting connections are here shown in the form of a complete lazy-tong or diamond-frame linkage. This linkage at each side of the door is composed of crossing levers 20^a, 20^b, which are pivoted to each other at their centers, as shown at 21^a, and at their ends to each other and to the upper and lower portions of the slats 11^a as shown at 22^a, 22^b. The pivots 21^a are extended and operate in the guides 41^a, which are similar to the 90 guides 41 already described. In this construction, it will be seen, the levers are unconnected with the slats at their central pivots, and each of the levers 20^a is pivoted at its ends to alternate slats while the complementary lever 20^b is pivoted at its ends to the slat between these two. In the other construction the slats themselves take the place of these levers 20^b. At the top the diamond-frame is completed by two short 105 levers 24^a, 24^b, which are pivoted at their upper ends on the supporting rod 26^a, which passes through castings secured to the narrow top slat 12^a. At the bottom the diamond-frame may be similarly completed. 110 The door may be counterweighted and operated in the same manner as in the other construction.

The construction of Figs. 11 and 12 also 115 illustrates the fact that the double-walled door formed by the overlapping slats may be off center with respect to the linkage and the guides. This construction may be employed when it is desired to flash the sides of the door opening at the outside only. In 120 this construction the levers of the lazy-tong linkage may be straight, since if the sides of the door opening are flashed at the outer side only the recesses in the slats through which the levers pass may be extended at 125 the inner side to accommodate straight links when the door is collapsed.

As already indicated the door may be provided with a wicket; and an important feature of such wicket is that it is collapsible 130

with the main door, of which it forms a part. This wicket is formed of the collapsible group of short slats 11^b and a short bottom slat 13^b, which are connected and supported by lazy-tong linkages corresponding to the main linkages of the door. The linkages of the wicket comprise levers 20^c, 24^c and 25^c, the pivots of which are in transverse alinement with the pivots of the main linkage. The lowermost pivot is formed by a section of the transverse rod 29, which section may be connected to and disconnected from the other sections by suitable means, such as the slideable sockets 50 having operating knobs 51 projecting through small slots in the bottom of the door. At the top these linkages at the sides of the wicket are preferably supported on the rod 27, which extends across the door and is connected to the counterweights. The said rod is accordingly disposed just over the wicket door; and another advantage of disposing this rod at a distance above the bottom of the door is that it avoids the necessity of making the travel of the counterweights so great as to require wells extending below the bottom of the door.

When the wicket is expanded and connected to the bottom rod 29, or to the bottom of the main door in some other manner, it acts merely as part of the main door. Its linkages being in alinement with the main linkages, its slats move in exactly the same manner as the slats of the main door with which they are alined. While the rod 29 has been shown severed, it will be understood that it might extend all the way across the door in one piece, suitable provision being made for fastening the bottom of the wicket thereto. When it is desired to open the wicket only, the catches at the bottom are released and the wicket is raised, its linkages acting independently of the main linkages. As indicated in Fig. 1 the slats of the wicket-door may be caused to flash the sides of the wicket-door opening in the main door. To this end the slats 11^b, 13^b are provided at the ends with projections which extend over the adjacent ends of the severed slats of the main door. These projections continuously overlap each other when the door is down, so as to leave no opening for admission of heat or the weather. It will be understood that these flashing projections are formed in the same manner as the flashing projections 42, that is to say, by cutting out or recessing the ends of the wicket-door slats.

From the foregoing description the general operation of the door will be readily understood. When closed it is double-walled throughout, containing an air space which prevents the transmission of great heat from one side to the other. When raised or collapsed it nests automatically

in a compact manner at the top or at one side of the opening. At the side next to the weather, and in fact at both the inner and outer sides, the door is entirely self-flashing, and this flashing is of a very effective character because the weight of the door itself causes the edges and faces of the slats to contact with a positive pressure. The degree of this pressure may be varied by varying the amount of counterweighting. The door affords a practically impervious protection against even a driving rain, because the water would have to make its way through tight joints at the outer side, then pass upward between the walls of the door, only to encounter another set of tight joints at the inner side of the door. Even a stream from a hose would be unable to get through the door. In addition to its fire-and-weather-proof qualities, the door has the advantages of being entirely accessible for painting, inspection and repair and of making it possible to remove and replace a slat when necessary with expedition and convenience. The door also lends itself to ventilating purposes. Thus, as indicated in Fig. 9, the door may be slightly raised, when all the slats swing away from each other sufficiently to give a louvered effect by partially opening the doorway. The extent of the ventilation openings is readily adjustable, and even a very slight movement of the door affords some ventilation. The door may be held at any height by the counterweights assisted by the friction of the pulleys, gears, etc.; or if it is desired to have the door decidedly overbalance the weights, or if there are no weights, any suitable devices may be provided for holding the door either open or in a ventilating condition.

It will be understood that the invention is not limited to details and that numerous changes may be made without departing from its scope. It will be apparent that those slats which serve as parts of the lazy-tong linkage may be reinforced if desired. It will also be obvious that the door or shutter may be arranged to operate sidewise across the door or window opening, instead of being raised and lowered, that is to say, the slats may be approximately vertical instead of horizontal.

Fig. 4 indicates the fact that the structure may be operated by a fusible link, so that the door is released to close the door or window opening by its own weight, or by other suitable means, in case of fire or of dangerously high temperature. To this end a fusible link or section is shown at 55 in the cable 32. It will be understood that this fusible section is duplicated in the cable at the opposite margin of the door or window opening (not shown in this view) and that when these links are fused the door or shutter is 130

- free to descend of its own weight. If the fusible links are interposed in the connections between the collapsible structure and the counterweights (where counterweights are employed) fusing of the links frees the structure of these weights, so that it closes instantaneously. However, the fusible links may obviously be disposed elsewhere.
- What I claim as new is:
1. A collapsible door or the like having a plurality of slats mounted to turn, each slat provided with a plurality of chambered portions, said slats forming spaced walls when closing the doorway and means for turning and collapsing said slats.
  2. In a collapsible door or the like, the combination of a plurality of slats mounted to turn each provided with a chambered portion and connections with said slats which turn and collapse them, the chambered portions of adjacent slats facing each other and forming a double walled door when the doorway is closed.
  3. An extensible and collapsible double walled door or the like comprising a plurality of slats mounted to turn each slat provided with a bent portion to form an air chamber, the bent portion of adjacent slats overlapping to form interspaces when the door is extended and means for extending and collapsing said door.
  4. A collapsible double walled door or the like comprising a plurality of slats mounted to turn each curved to form chambered portions at opposite ends of the slats, said slats, when the door is extended, co-operating with each other to form spaced inner and outer walls, and connections to said slats to turn and collapse them.
  5. In a double walled door or the like comprising a plurality of slats mounted to turn and bent or curved to form chambers, adjacent slats being arranged so as to meet edge to face and form double walls with interspaces, and connections to said slats to turn and collapse them.
  6. A collapsible double walled door or the like comprising a plurality of turning slats overlapping when the door is extended, said slats being provided with chambers and co-operating with each other to form inner and outer walls with interspaces, the upper and lower portions of the slats forming parts of the respective walls and their intermediate portions forming walls for said interspaces, and means for turning said slats.
  7. A collapsible double walled door or the like comprising a plurality of turning slats which when the door is extended co-operate with each other to form a series of chambers, the slats contacting to form joints at the inner and outer sides of the door which joints are out of horizontal alignment and means for turning said slats.
  8. A collapsible double walled door or the like comprising a plurality of bent or curved slats mounted to turn and connections whereby the door may be collapsed and extended, said slats overlapping when the door is extended to form a continuous series of chambers, the upper and lower edges of the slats taken alternately being spaced apart along intermediate portions of the slats between said intermediate portions forming division walls between said pockets and means for turning and collapsing said slats.
  9. A collapsible double walled door or the like comprising a plurality of ogee turning slats and connections to said slats for turning and collapsing them whereby the door may be collapsed or extended with the slats in overlapped relation so as to form spaced walls.
  10. A collapsible double walled door or the like comprising a plurality of bent slats mounted to turn which overlap so as to form continuously spaced inner and outer walls, and lazy-tong connections with said slats whereby the door may be collapsed and extended.
  11. The combination of a collapsible double walled door consisting of overlapping slats mounted to turn and collapse and lazy-tong connections between said slats for turning and collapsing them.
  12. In a collapsible double walled door or the like, the combination of a plurality of slats having chambered portions which overlap and thereby form inner and outer walls with an interspace, and levers pivoted centrally to the intermediate portions of the several slats, the ends of each lever being pivoted to the upper and lower portions of the slats adjoining the slat to which it is pivoted centrally.
  13. In a collapsible door or the like, the combination of a plurality of slats having chambered portions which overlap and thereby form inner and outer walls with an interspace, and lazy-tong linkages comprising levers each of which is pivoted at its ends to alternate slats and intermediate its ends to the slat between.
  14. In a collapsible double walled door or the like, the combination of a plurality of slats having chambered walls which overlap and thereby form inner and outer walls with an interspace, and a lazy-tong linkage comprising levers fulcrumed intermediate and pivoted at their ends to alternate slats.
  15. In a collapsible double walled door or the like, the combination of slats having chambered portions, lazy-tong linkages collapsibly supporting the same, a support for the upper end thereof, flexible connections extending upward from the lower portions of said linkages, and means for operating said connections.

16. In a collapsible double walled door or the like the combination of a plurality of slats having chambered portions, said slats coöperating with each other when the door is extended so as to form interspaces between the walls and being recessed at their ends and levers received within said recesses connecting and collapsibly supporting said slats.
17. In a collapsible double walled door or the like the combination of a plurality of slats having overlapping portions, said slats being shaped so that their overlapping portions form inner and outer walls with interspaces, said slats having recesses in their ends, which recesses are covered by the portions forming one of said slats and levers received within said recesses connecting and collapsibly supporting said slats.
18. In a collapsible double walled door or the like, the combination with members at the sides of the door or window opening, of a plurality of overlapping turnable slats recessed at their ends to receive said members and to form flashing extensions which extend over the same, and connections supporting said slats for turning them and permitting the door to be collapsed to open the door or window opening.
19. In a collapsible door or the like, the combination with members at the sides of the door or window opening, of a plurality of collapsibly-supported overlapping turnable slats coöperating when the door is extended to form spaced walls, said slats being recessed at their ends to receive said members and to form flashing extensions which extend over both sides of said members, said recesses being formed entirely in portions of the slats which are internal to both said walls and means for turning said slats.
20. In a collapsible double walled door or the like, the combination of a plurality of slats having portions which form inner and outer walls with an interspace crossed by intermediate portions of the slats, collapsible linkages supporting said slats, and vertical guides, said slats being cut out at their ends to receive said guides and to form flashing extensions which extend across said guides and form the lateral portions of one of said walls.
21. In a collapsible double walled door or the like, the combination of a plurality of slats having portions which overlap in such manner as to form inner and outer walls with an interspace crossed by intermediate portions of the slats, collapsible linkages connecting said slats and having pivot projections, and vertical guides receiving said pivot projections, said intermediate portions of the slats being cut away at their ends to receive said guides and to form flashing extensions which extend across said
- guides and form the lateral portions of one of said walls.
22. In a collapsible double walled door or the like, the combination of a plurality of slats having portions which overlap in such manner as to form inner and outer walls with an interspace crossed by intermediate portions of the slats, collapsible linkages supporting said slats and having pivot projections, and vertical guides receiving said pivot projections.
23. A collapsible door or the like, comprising a plurality of slats adapted to overlap and formed with upper and lower portions offset laterally so as to constitute parts of spaced inner and outer walls, the intermediate portions of the slats being recessed at the ends, pivots secured to said recessed intermediate portions, and members carrying pivots secured to the inner faces of the upper and lower portions of each slat at the ends, in combination with levers pivoted centrally on the first-mentioned pivots and at their ends on the other pivots.
24. A collapsible door or the like comprising a plurality of slats adapted to overlap and formed with upper and lower portions offset laterally so as to constitute parts of spaced inner and outer walls, the intermediate portions of the slats being recessed at the ends, pivots secured to said recessed intermediate portions, and members carrying pivots secured to the inner faces of the upper and lower portions of each slat at the ends, in combination with levers pivoted centrally on the first-mentioned pivots and at their ends on the other pivots, and guides receiving the outer ends of the first-mentioned pivots.
25. In a collapsible double walled door or the like, the combination with members at the sides of the door or window opening, of a plurality of tiltable slats collapsibly connected and coöperating when the door or window is extended to form spaced walls, said slats being provided at their ends with flashing extensions extending across said members.
26. In a collapsible door or the like, the combination with members at the sides of the door or window opening, of a plurality of slats collapsibly connected and coöperating when extended to form spaced walls, said slats being recessed at their ends to receive said members and to afford flashing extensions extending across said members and forming the lateral portions of one of said walls, and collapsible linkages connecting the slats, said linkages being accommodated in said recesses and guided by said members.
27. A collapsible door or the like comprising a plurality of tiltable slats and a lazy-tong linkage one or more links of the linkage being formed by said slats.

28. A collapsible door composed of a plurality of slats, some of which are of less length than the remaining slats so as to provide a wicket opening, in combination with 5 a collapsible and extensible wicket carried by the door and composed of a collapsible group of slats for said wicket opening.
29. A collapsible door comprising a plurality of slats having collapsible connections, and a collapsible wicket-door inserted 10 therein and formed of collapsible slats and adapted to collapse with the main door.
30. A collapsible door comprising a plurality of slats having collapsible connections, said slats being mounted to turn, and 15 an extensible and collapsible wicket door inserted therein formed of a collapsible group of slats, which slats are mounted to turn when the wicket is collapsed or extended.
31. A collapsible door comprising a plurality of slats and means whereby the same may be nested or extended across the door opening, certain of said slats being severed 20 to afford a wicket-door opening, and a wicket-door formed of slats similarly connected, the slats of the wicket-door flashing 25 at their ends with the ends of the severed slats.
32. A collapsible door comprising a plurality of slats and linkages collapsibly supporting the same, certain of said slats being 30
- severed to afford a wicket-door opening, a rod extending across the door and connected at its ends to said linkages, and a wicket-door comprising linkages and slats supported from said rod. 35
33. A collapsible door comprising a plurality of slats and linkages collapsibly supporting the same, certain of said slats being severed to afford a wicket-door opening, 40 a rod extending across the door and connected at its ends to said linkages, a wicket-door comprising linkages and slats supported from said rod, and flexible cables or the like connected to the ends of said rod to control the opening and closing of the door. 45
34. In a collapsible double walled door or the like comprising in combination a plurality of slats having chambered portions which overlap and thereby form inner and 50 outer walls with interspaces, and levers pivoted centrally to the intermediate portions of the said slats the distance between the pivots being less than the length of a slat. 55

In testimony whereof, I have signed my name to this specification, in the presence of two subscribing witnesses.

GEORGE W. KNOFF.
